SKI-SCOOTER

Otto H. Dunkel, Detroit, Mich.

Application November 21, 1946, Serial No. 711,349

3 Claims. (Cl. 280—23)

1

This invention relates to winter sporting equipment and particularly to a skiing device upon which a rider may sit or stand.

An important object of this invention is to provide an improved type of device for gliding over snow and ice which is formed of parts economical to manufacture and assemble and which provides a place for the rider to either stand or sit at his convenience. Another object of the invention is to provide a novel type of apparatus for winter sports which is provided with a snow engaging runner of a size to accommodate both feet of the occupant and a handle and seat construction which are associated together in a novel manner to distribute the weight of the rider and mutually strengthen one another. A further object of the invention is to provide a novel device of this character which is in the form of a ski-scooter and is provided with a handle adjustable in height to suit the convenience of the rider and a resiliently supported seat which is constructed in such a manner as to prevent injury in the event of a mishap. A novel feature of the device is the shape of the seat support which not only serves as a spring for the seat but is so shaped and related to the other parts of the device that it serves as a brace for the legs of the rider.

Other objects, advantages and meritorious features of this invention will become more fully apparent from the following specification, appended claims and accompanying drawing, wherein:

Fig. 1 is a perspective view of the assembled skiing device of this invention.

Fig. 2 is a vertical sectional view through the skiing device of Fig. 1 along line 2—2 thereof showing parts of the device in section, and

Fig. 3 is a horizontal sectional view along line 3—3 of Fig. 1 illustrating in larger scale the method of connecting the upright handle support and seat support together.

The preferred embodiment of the invention is illustrated in the drawing and comprises a ski member or runner 10 preferably formed of hard wood having an upwardly curved and pointed front end section 12 in a manner characteristic of ski runners. The runner 10 is wider than the normal ski runner and is of such a width as to receive both feet of the rider in close side-by-side relation. Preferably the lateral dimension of the runner 10 is slightly greater than twice the width of normal sized shoes. At approximately midway between the ends of the

runner a slightly raised or elevated platform 14 is provided as indicated in Fig. 1. Supported on this raised or elevated portion of the runner is an upright support generally indicated at 16 carrying a handle which may be grasped by both hands of the rider. The upright supporting structure as shown in Fig. 2 preferably comprises a metal tubular member 18 supported at its lower end by a collar 20 having a widened base secured in any suitable manner to the elevated portion of the runner, such as by bolts 22. The upper end of the tubular member is open and telescopingly receives a second tubular member or shaft 24 which is preferably of such a dimension as to slidably engage the inner surface of the tubular member 20. Supported on the upper end of the tubular member 24 is a cross member 26 serving as the handle previously described. As shown, the upright handle supporting structure 16 is mounted adjacent to the front end of the raised platform 14 of the runner.

Rearwardly of the upright handle supporting structure 16 is a seat 30 upon which the rider may sit. This seat is supported by a curved member 32 which is bowed forwardly for connection to the upright support 16 intermediate its ends and thence downwardly and rearwardly for attachment to the raised portion 14 of the runner. The seat supporting member 32 is preferably made of metal tubular material as shown in Fig. 3 and of such resiliency that the seat 30 is spring supported. In order to mutually support one another, the upright structure 16 and the seat supporting member 32 are interconnected preferably in the manner illustrated in Fig. 3. An elongated bolt member 34 is provided which extends through both the tubular member 18 and forwardly bowed portion of the tubular member 32, and a wing-out 36 or other suitable means on the end of the bolt is employed for tightly securing the two tubular members together.

By providing a tubular member 32 for the seat support there is no danger of injury in the event that the ski-scooter should strike some obstruction and is damaged. The tubular member 32 will not break in the event of such impact but merely bend if the impact is of such a degree of force as to damage the seat supporting member. The forward extension and connection of the seat supporting member 32 to the upright 16 provides a brace between the legs of the rider which assists the rider in his swaying movements from one side to the other to tilt the

device for making turns. The tubular dimension of the seat supporting member 32 is such that it does not interfere with the legs of the rider and in use the feet of the rider are supported on the elevated portion 14 immediately rearwardly of the upright 16 and side by side. The bracing action of the tubular member between the legs provides a greater control over the movement of the ski-runner. As the rider leans or sways from one side to the other, he can control the action of the runner by pressure exerted by his legs upon either side of the seat supporting member 32 along that portion which extends between his legs. As shown in Fig. 3, the seat supporting member has a lateral dimension which is considerably less than the width of the runner and extends in a vertical plane corresponding with the longitudinal median line of the runner. Thus the legs of the rider can conveniently embrace the member and at the same time receive a bracing support therefrom when leaning from one side to the other.

Preferably the handle 26 is adjustable vertically to suit the convenience of the rider. This is accomplished by providing each telescoping portion of the two tubular members 18 and 24 with a series of holes 38 which extend from one side to the other and are vertically spaced apart. To receive these parts in adjusted position, one or more bolts 40 are employed which extend through registering holes in the two members. Preferably two such bolts are used as shown and they are secured in place against unintentional removal by wing-nuts 42. It is evident that when the height of the handle is desired to be adjusted, the wing-nuts and bolts are removed and the shaft 24 of the handle shifted to the desired position at which time the bolts are re-inserted and secured in newly aligned holes.

In use, the rider sits on the seat 30 with his two legs embracing the seat supporting member 32 and his feet arranged side by side on the elevated portion 14 behind the handle supporting structure 16. Either one or both hands grasp the handle 26. By leaning or swaying from side to side while in movement the direction in which the runner is advancing can be changed. The four points of contact provided by the seat, handle, foot rest and leg brace assure complete control over the device. At any time the rider may raise himself to a standing position and while in this position the leg brace formed by the seat supporting member will assist in maintaining the rider's balance.

What I claim is:

1. A skiing device comprising, in combination, a single elongated runner having a width approximating twice the width of a shoe worn by the rider thereof, an upright member secured at its lower end to the runner approximately half-way between the ends thereof and adapted to carry a handle on the upper end, a cylindrical frame member bent into a generally U-shaped formation mounted on the ski-scooter rearwardly of the upright member in the vertical plane of the longitudinal median line of the runner and with the end sections thereof projecting rearwardly in vertically spaced apart relationship, means connecting the closed end of the frame member to the upright member intermediate the height of the latter, and means securing the lower horizontal end section of the frame member to the runner rearwardly of the upright member, the diameter of the frame member being consider-

ably less than the width of the runner whereby a rider may with both of his feet on the runner straddle the frame member and guide the movement of the device.

2. A skiing device comprising, in combination, a single ski-runner having a width substantially twice the width of a shoe worn by the rider of the device, a substantially upright member secured at its lower end to the runner approximately mid-way between the ends thereof and carrying on the upper end thereof a laterally extending handle, a tubular member of inherent resiliency bowed intermediate its ends into a substantially U-shaped formation and mounted on the device rearwardly of the upright handle carrying member with the end sections thereof extending substantially horizontally in vertically spaced apart relationship and with the intermediate bowed portion projecting forwardly of the device and contacting the upright handle carrying member, means securing the bowed contacting portion of the tubular member to the upright handle carrying member, means securing the lower end section of the tubular member to the runner, the upper end section of the tubular member forming a support for a seat and by virtue of its inherent resiliency imparting a springing movement to the seat, and the diameter of the tubular member being substantially less than the width of the runner whereby a rider may with both of his feet on the runner straddle the tubular member and guide the movement of the device.

3. A skiing device comprising, in combination, a single ski-runner having a width substantially twice that of a shoe worn by a rider of the device, a substantially upright member secured at its lower end to the runner approximately mid-way between the ends thereof and carrying a laterally extending handle on the upper end thereof, a seat, a tubular member of inherent resiliency bowed intermediate its ends into a U-shaped formation and carrying the seat on one end thereof, means securing the other end of the U-shaped tubular member to the runner rearwardly of the upright handle carrying member so that the tubular member extends in the vertical plane of the longitudinal median line of the runner with the intermediate bowed portion thereof contacting the handle carrying member and with the seat supported end thereof disposed in spaced relation above the runner for free flexing movement relative thereto, means securing the contacting portion of the U-shaped member to the handle carrying member, the resilient tubular member having a diameter substantially less than that of the runner whereby the legs of the rider may with both of his feet on the runner straddle the tubular member and guide the movement of the device.
